CONTOUR CHAIR WITH ADJUSTABLE SEAT

Leo C. Malco, Long Beach, Calif.

Application April 17, 1951, Serial No. 221,377

2 Claims. (Cl. 155—115)

1

This invention relates to a contour chair with a portion of the seat being vertically adjustable to different sizes so that a person sitting in the chair will have a foot or leg rest somewhat elevated above the seat level of the chair.

An object of my invention is to provide a contour chair in which the front portion of the seat is so mounted that it can be raised vertically above the level of the rear portion of the seat.

Another object of my invention is to provide a novel contour chair in which the front portion of the seat is hinged to the frame of the chair and can be moved upwardly so as to assume an elevated position above the normal horizontal position of the seat.

A feature of my invention is to provide a contour chair with an adjustable seat so arranged that the front portion of the seat can be raised vertically as desired and at the same time the back is hinged and can be pivoted about its hinge to provide a semi-reclining position and all of the parts can be fixed in their adjusted position, as desired by the user.

Another feature of my invention is to provide a novel contour chair with an adjustable seat, in which the advantages of an adjustable seat, as well as an adjustable back, are provided in a chair in which the normal chair contours are preserved so that the chair does not have an unusual style or shape but, on the contrary, conforms to the modern or period design of furniture.

Other objects, advantages and features of invention may appear from the accompanying drawing, the subjoined detailed description and the appended claims.

In the drawing:

Figure 1 is a side elevation of one type of my contour chair in normal position of the seat.

Figure 2 is a side elevation of the same showing a portion of the seat in raised position.

Figure 3 is a side elevation of a modified form of seat mount.

Figure 4 is a view similar to Figure 3 in which the seat portion is elevated.

Figure 5 is a side view of still another type of link mount between the seat and the frame.

Figure 6 is a side elevation similar to Figure 5, showing the seat portion in raised position.

Figure 7 is a side elevation of still another link type of connection between the seat and the frame.

Figure 8 is a view similar to Figure 7 showing the seat portion in raised position.

Figure 9 is a side elevation of still another type of leg rest for a chair.

2

Figure 10 is a view similar to Figure 9 showing the leg rest in raised position.

Figure 11 is a side view of one of the clamps for the hinged portions of the chair.

Figure 12 is a top plan view of the same.

Figure 13 is a fragmentary side elevation of the slotted link connection to the seat portion as shown in Figure 4.

Referring more particularly to the drawing, the numeral 1 indicates the usual chair frame which includes the usual legs, all of which may be styled as desired. A back 2 is hingedly attached to the frame 1 at 3, and may be moved around this hinge as desired by the user. One method of securing the back 2 in its adjusted position is an arm rest 4, provided with a slot 5, into which a bolt 6 extends, this bolt fitting in the side of the back 2. The bolt rides in the groove 5 and may be tightened against the arm 4 thus holding the back 2 in its adjusted position.

The seat includes a fixed rear portion 7 which rests in the frame 1 of the chair and an adjustable front portion 8. The seat portions 7 and 8 may be padded as desired and when in the lower position, shown in Figure 1, form the usual width and depth of a chair seat. The front portion 8 of the seat can be raised above the position shown in Figure 1 and thus form an elevated support for the legs of the user. This vertical movement of the front seat portion 8 is accomplished by a rack 9 which depends from the seat portion 8 and is guided in the frame 1 of the chair. This rack is engaged by a manually rotatable gear 10, thus enabling the seat to be raised or lowered in an amount desired by the user. The gear 10 can be clamped and prevented from rotating by a friction clamp such as the hinge shown in my co-pending application, Serial No. 284,577, filed April 26, 1952. A foot rest 11 is mounted in the seat portion 8. In the raised position of the seat portion 8, the back rest 2 is lowered, as shown in Figure 2, thus providing a more comfortable semi-reclining position for the user.

In Figure 3 the frame portion 12 is again formed in any style desired and the back 13 is attached to this frame in the usual and well known manner of furniture construction. A rear seat portion or section 14 is also provided, which is preferably somewhat less than one-half of the entire seat area of the chair. The front seat portion 15 of the chair is pivotally attached to the frame 12 by the pivot 16, and this pivot may have a friction lock or a lock of any other usual type so that the front seat portion 15 can be held in a tilted position, as shown in Figure 4. The

friction lock 16' consists of plates 16^a secured to the frame of the chair and an overlapping plate 16^b secured to the seat 15, these plates being engaged by friction discs 16^c which are clamped by the nut 16^d. The seat portion 15 also includes a depending leg portion 17, which is integral with the seat 15. In the tilted position of the seat 15, the leg portion 17 assumes a substantially horizontal position, as shown.

To further support and stabilize the seat 15 in its tilted position, I provide a pair of links 18 which are pivotally attached at one end to the frame 12 and at the other end to the front portion of the seat 15. The links 18 are slotted as shown at 18', thus permitting swinging movement of the links.

In Figures 5 and 6 I have shown a seat construction quite similar to that shown in Figures 3 and 4, in which the back rest 19 is substantially identical to the construction described for the back 13. The front seat portion 20 is angularly tiltable relative to the rear seat portion 21 by means to the two links 22 and 23 which are provided at one end of the frame 24, and at the other end to the seat portion 20, as shown. The pivotal connection of the links 22 and 23 to the frame 24 may have friction locks so as to hold the seat portion 20 in its tilted position. These friction locks are of the same type as described above in the description of Figure 3.

In Figures 7 and 8 I have shown the construction which is somewhat similar to that shown in Figures 1 and 2, in that the front seat portion 25 is moved vertically above the plane of the rear seat portion 26. The back 27 is again pivotally mounted on the frame 28 by the bolts or pins 27'. A friction lock, such as described for Figure 3, may be mounted on the pins 27'. The front seat portion 25 is attached to the frame 29 by means of the two links 29 and 30 which are 40 pivotally secured at one end to the frame 28 and at the other end to the front seat portion 25, substantially as shown.

In Figures 9 and 10 the back 31 and seat 32 are mounted on a frame 33 in the usual and well known manner and are not necessarily adjustable.

To provide a leg rest, a transverse pad 34 is pivotally mounted on the frame 33 by links 35 which enables the user to swing the pad upwardly as shown in Figure 10 to a position to support the legs of the user. Also, the front portion of the chair 36 is pivotally attached to a link 36' by the pivot 37, thus enabling the part 36 to be swung upwardly to act as a foot support. The link 36' is pivoted to the frame 33 of the chair by the pin 38, which pin also pivots the link 35 as shown.

Having described my invention, I claim:

1. A contour chair with adjustable seat comprising a frame, a rear seat portion mounted on said frame, a front seat portion, said front seat portion including a material part of the entire area of the seat, a back rest mounted on the frame, and means coupling the front seat portion and the frame to permit vertical movement 20 of the front seat portion above the plane of the rear seat portion, said means comprising a link pivotally attached at one end to the front seat portion and at the other end to the frame.

2. A contour chair with adjustable seat comprising a frame, a rear seat portion fixedly mounted on the frame, a back rest rising from the frame and mounted thereon, a front seat portion, said front seat portion forming a material part of the outer area of the seat, means 30 pivotally mounting the inner end of said front seat portion to the frame, and a link pivotally secured at one end to the front seat portion and at the other end to the frame.
